No. 652,807.

Patented July 3, 1900.

A. L. OVERCASHIER:
SHOE POLISHING CABINET.

(Application filed Oct. 27, 1899.)

(No Model.)

UNITED STATES PATENT OFFICE.

ALFRED L. OVERCASHIER, OF PITTSBURG, PENNSYLVANIA.

SHOE-POLISHING CABINET.

SPECIFICATION forming part of Letters Patent No. 652,807, dated July 3, 1900.

Application filed October 27, 1899. Serial No. 735,003. (No model.)

To all whom it may concern:

Be it known that I, ALFRED L. OVERCASHIER, a citizen of the United States, residing at Pittsburgh, in the county of Allegheny and State of Pennsylvania, have invented or discovered a new and useful Improvement in Shoe-Polishing Cabinets, of which the following is a full, clear, and exact description, reference being had to the accompanying drawings, forming part of this specification, in which—

Figure 1 is a perspective view of the exterior of my improved shoe-polishing cabinet, Fig. 2 is a vertical longitudinal section showing the foot-rest depressed. Fig. 3 is a view of the stand with the foot-rest elevated and the outer case removed. Fig. 4 is a sectional detail view of the foot-rest and its supporting post and standard, partly in section. Fig. 5 is a detail view of the supporting-post without the foot-rest. Fig. 6 is a horizontal cross-section taken in the line VI VI of Fig. 2. Fig. 7 is a detail perspective view of the locking device by which the outer case is retained in position on the standard. Fig. 8 is a perspective detail view of one of the supporting-legs.

My invention consists of a combination shoe-polishing cabinet and stool, and comprises an adjustable foot-rest mounted in a supporting-standard provided with a receptacle for polishing articles and materials, with an inclosing outer removable case having a top adapted to serve as a stool.

Referring to the drawings, 2 is a central standard mounted on legs 3, of wood or metal, provided on the bottom with rubber or adhesive material 4 to prevent slipping on the floor. The standard is provided with a hollow center, in which is vertically mounted the post 5, of tubing, provided at one side with a series of socket-holes 6, adapted to receive the end of a spring-actuated locking-pin 7, provided with a button 8, by which it may be withdrawn to change the location of the post.

It will be understood that any other suitable locking device may be employed that will positively hold the post at any desired position in the standard.

9 is a foot-rest faced with rubber 10, pivotally mounted at 11 between upwardly-extending bearings of the post, and pivoted at

12 to the underside of the foot-rest is a curved segmental locking-arm 13, provided with a series of notches 14, adapted to engage the 55 thickness of the tubing at the bottom of a vertical slot 15, through which the curved arm 13 passes, a similar slot 16 being made on the opposite side and both slots being of sufficient length to admit of variations of position of the arm. Owing to such variations the angles of the notches are so located as to always bear squarely against the edge of the tubing, and in the operation of adjusting the 60 foot-rest to a position approximating the horizontal the arm may be disengaged by simply raising the heel, while it will be firmly locked against downward pressure of the foot at whatever angle it may be set.

It will be noted that auxiliary slots 17 are 70 made in the standard 2 to permit of passage of the arm in a lowered position.

Mounted between the legs 3 at the base is a pan 18, preferably circular in form and of sufficient depth to insure holding capacity for 75 polishing pastes and material, and to the bottom of the pan or connected in any suitable manner is a flat tongue 19, lined on the bottom with some adhesive material 20, as rubber, bearing on the floor. The operator by 80 placing his foot upon this tongue easily holds the stand against movement or tilting.

When not in use the entire cabinet is covered by a cylindrical apron 21, made of sheet metal, which neatly fits around the legs, resting on recessed ledges 22, and at two or more points the metal is cut and turned inwardly, forming a tongue 23, which registers with and engages in a horizontal groove 24, cut in the face of the leg, and when thus engaged at two 90 or more opposite points the apron is firmly retained against removal, entirely incloses, conceals, and covers the stand, and forms a convenient stool, being provided at the upper end with a seat-top 25, of wood, having 95 a hand-hole 26, by which it may be lifted from place to place or away from the cabinet.

My invention will be appreciated by those familiar with the use of such devices, and it is peculiarly adapted to the ends in view. It 100 is very compact, may be adjusted easily and quickly to different heights and angles, embodies a convenient receptacle in the base, and when closed forms a convenient stool,

which is both serviceable and ornamental. It is particularly adapted for use in barbershops, hotels, or private use, and a particular feature of advantage will be found in the 5 clearance from obstruction around the base of the foot-rest, permitting use of polishing brushes or cloths.

What I claim is—

1. A hollow standard provided with supporting-legs, a post adjustably mounted therein, a foot-rest pivotally mounted on the post, and a pivoted supporting-arm therefor provided with means for locating the foot-rest at varying angles.
- 15 2. A hollow standard provided with supporting-legs, a post adjustably mounted therein, a foot-rest pivotally mounted on the post, and a pivoted curved supporting-arm, provided with notches adapted to engage a locking-stop in the post and to support the foot-rest at varying angles.
- 25 3. A hollow standard provided with supporting-legs, a tubular post adjustably mounted therein, a foot-rest provided with adhesive material on its upper face pivotally mounted on the top of the post, a curved supporting-arm pivotally attached at one end to the under side of the foot-rest, passing through slots in the post and provided with notches on its 30 outer edge adapted to engage the edge of the post and to support the foot-rest at varying angles.
- 35 4. A hollow standard provided with supporting-legs, a tubular post adjustably mounted therein, a foot-rest provided with adhesive material on its upper face pivotally mounted on the top of the post, a curved supporting-

arm pivotally attached at one end to the under side of the foot-rest, passing through slots in the post and provided with notches on its 40 outer edge adapted to engage the edge of the post and to support the foot-rest at varying angles, and a pan-receptacle mounted between the legs at the base.

5. A shoe-polishing cabinet comprising a 45 standard, a post adjustably mounted therein, a foot-rest pivotally mounted on the post, a pivoted curved supporting-arm therefor provided with means for locating the foot-rest at varying angles, and a removable cover provided with a seat-top.

6. A shoe-polishing cabinet comprising a standard, a post adjustably mounted therein, a foot-rest pivotally mounted on the post, a pivoted curved supporting-arm therefor provided with means for locating the foot-rest at varying angles, a pan-receptacle in the 55 base, and a removable cover provided with a seat-top.

7. A shoe-polishing cabinet comprising a 60 standard, a post adjustably mounted therein, a foot-rest pivotally mounted on the post, a pivoted curved supporting-arm therefor provided with means for locating the foot-rest at varying angles, a pan-receptacle in the base, 65 a holding device subject to foot-pressure, and a removable cover provided with a seat-top.

In testimony whereof I have hereto set my hand.

ALFRED L. OVERCASHIER.
